CUSHIONING MEANS FOR EGG CARTONS

Filed July 28, 1927

Inventor:
By John E. Walsh,
Wm F. Freudenreich
Atty:

UNITED STATES PATENT OFFICE

JOHN E. WALSH, OF CHICAGO, ILLINOIS, ASSIGNOR TO SELF LOCKING CARTON COMPANY, A CORPORATION OF ILLINOIS

CUSHIONING MEANS FOR EGG CARTONS

Application filed July 28, 1927. Serial No. 208,901.

The present invention has for its object a simple and novel attachment for a carton divided into individual cells or compartments as for example an egg carton that 5 will form an effective cushion for eggs or other articles housed within the cells or compartments.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a top plan view of one end of an open carton provided with one of my improved cushioning devices; Fig. 2 is a 20 transverse section through the carton filled with eggs and closed; Fig. 3 is a view of a fragment of the cushioning element in a flattened condition; and Fig. 4 is a view similar to Fig. 2, showing a modified form 25 of cushion.

Referring to the drawing, 1 represents a carton provided with a cover 2. The carton is divided into a plurality of cells or individual compartments arranged in two longitudinal rows, by means of a series of 30 transverse partitions 3 and a central longitudinal partition 4. The carton itself may take any usual or suitable form.

In accordance with my invention, I provide each cell or compartment with a swing 35 preferably supported from the partition members, in which swing the egg or other article to be packaged rests. The eggs or other articles are thus suspended above 40 the bottom of the carton and out of contact with the sides, so as to protect them against blows struck against the bottom or sides of the carton.

In the preferred embodiment of my invention I employ for the cushioning means 45 a sheet of strong paper having a width equal to the length of the carton and a length equal to about four times the depth of the carton; although the length may be varied 50 within wide limits as long as it is greater

than the width of the carton. The sheet or blank, indicated as a whole at 5, has longitudinal slots 6 and 7 cut in the upper and lower halves. These slots are equal in number to the transverse partitions and are 55 spaced apart from each other the same distance as are the transverse partitions. The blank is preferably scored along three parallel transverse lines, namely on the transverse central axis, as indicated at 8 60 and half way between the central axis and the top and bottom, as indicated at 9. Each slot is almost half as long as the blank. When the blank is folded along the scored lines so that an edge view thereof has the 65 appearance of the letter W, it may be inserted in the carton; the slots permitting it to be pressed down between the transverse partitions, while the central portion in the form of an inverted V embraces the longitudinal partition, resting at its apex on the latter. The marginal sections 10 in the blank at the outer ends of the slots rest on the transverse partitions, so that the sections between adjacent slots form swings 70 suspended from their upper ends on the longitudinal and transverse partitions. When an egg, for example, as indicated at 11, is placed in one of the compartments or 75 cells, it rests in the corresponding swing and is held away from the bottom and the adjacent side of the carton and also from the central longitudinal partition. Therefore if the carton is set down heavily or is struck 80 a blow, or is jarred, the egg will be protected and will also be prevented from striking the egg on the opposite side of the longitudinal partition.

If desired, the cushion may comprise a member corresponding approximately to 85 either the upper half or the lower half of the blank just described. When the cushion is in this form, it will be applied as shown in Fig. 4; the blank being folded once along a line corresponding with the line 9 in Fig. 3. The blank or cushion must be applied before the central longitudinal partition is inserted. Then, when the longitudinal partition is placed in position, it engages with 90 the blank along the line of the fold, and 100

5 presses the middle of the blank down toward or in contact with the bottom of the carton. This form of cushion serves to protect eggs or other articles against blows from without, but does not hold them away from the central longitudinal partition; and therefore does not possess all of the advantages of my invention in its preferred form.

10 Not only do the cushions protect the eggs or other articles, but they reinforce and stiffen the carton, so that the latter will not be nearly as susceptible to damage as it would without the presence of the cushions.

15 While I have illustrated and described with particularity only a single preferred form of my invention, with a single modification, I do not desire to be limited to the exact structural details thus illustrated and described; but intend to cover all forms and 20 arrangements which come within the definitions of my invention constituting the appended claims.

I claim:

1. The combination with a container having a longitudinal partition and transverse partitions extending across the latter and cooperating therewith to divide the container into two rows of compartments, of a 25 flexible sheet slotted between the ends to permit the portions between the slots to enter the compartments in the container while the ends are supported upon the tops of the transverse partitions, the parts being so proportioned that the portions of the sheet 30 between slots stand clear of the bottom of the container.

2. The combination with a carton in which is a multiple compartment filler formed by intersecting cross and longitudinal walls, of a suspension unit formed of 40 a single piece of yieldable material slotted to provide interconnected straps each of V-formation adapted for dependency within one filler compartment, the interconnections 45 between the straps being rested upon upper edges of the filler walls whereby to support the unit in suspended position, and the filler walls cooperating with the V-straps to provide seats for eggs or other objects, one 50 within each filler compartment, substantially as described.

In testimony whereof, I sign this specification.

JOHN E. WALSH.
